UNITED STATES PATENT OFFICE.

IRA H. SPENCER, OF WEST HARTFORD, CONNECTICUT. ASSIGNOR, BY MESNE ASSIGNMENTS, TO THE SPENCER TURBINE COMPANY, A CORPORATION OF CONNECTICUT.

ROTARY BLOWER.

1,288,728.

Specification of Letters Patent. Patented Dec. 24, 1918.

Application filed September 18, 1915 Serial No. 51,417.

To all whom it may concern:

Be it known that I, IRA H. SPENCER, a citizen of the United States, and a resident of West Hartford, in the county of Hartford and State of Connecticut, have invented a new and Improved Rotary Blower, of which the following is a specification.

My invention relates to the class of devices above named which devices comprise a fan or series of fans arranged upon a common shaft, and an object of my invention, among others, is the production of a blower that shall be extremely strong in its construction and able to withstand the strains incident to high peripheral speeds.

One form of device embodying my invention and in the construction and use of which the objects herein set out, as well as others, may be attained, is illustrated in the accompanying drawings, in which—

Figure 1 is a view in side elevation of a blower embodying my invention, the structure being partially broken away in central vertical section to show construction.

Fig. 2 is a face view of one of the blower sections looking in the direction of the arrow shown in Fig. 3.

Fig. 3 is a detail view, scale enlarged, of a portion of the shell and of one of the blower sections, the latter being partially cut away in central section to show construction and a portion of the section being broken out.

My invention is of particular value in connection with fans for effecting changes in air pressures for different purposes, it being my intention to provide a structure with which the desired results may be attained by rotating the fans at a minimum speed as compared with the peripheral speed thereof, that is, the fans being made large in diameter to produce the required peripheral speed and the construction being such that they will readily withstand the strains incident to this high peripheral speed.

The term "blower" has been used herein because it is a name commonly given to devices of this class, nevertheless the invention will be understood to exist in a structure whether it be used to raise pressures for certain purposes or to reduce them.

In the accompanying drawings the numbers 5 and 6 indicate the sections of a blower shell or case, that is composed of sheet metal, round in cross section, and supported in any suitable manner, as upon cross

pieces 7. Rings 8 closely fit the outer surface of the main section 5 of the shell at each end thereof and are secured thereto in any suitable manner, as shown herein, these rings being of L-shape in cross section with bolts 60 extending through the flanges and through end plates 9—10 to secure them in place. A second ring is employed surrounding the meeting ends of the main and motor sections 5 and 6, respectively, of the shell, the two 65 rings at this point being bolted together to clamp the end plate 10 between them. The end plates 9 and 10 are each provided with a lip 36 of a depth to inclose one of the surrounding rings and also inclose a gasket to 70 be hereinafter described. An inlet port 11 and an exhaust port 12 are formed through the plates 9 and 10 respectively, and a motor 13 is supported in any suitable manner in the motor section 6 of the shell. Gaskets 14 75 are clamped between the end plates and rings, as shown in Fig. 1 of the drawings, to prevent leaking at these joints.

The parts directly inclosing the fans and constituting the air passages are made up in 80 sections closely fitting the interior of the shell, as well as each other. Each section includes a division plate 15, a diffusion plate 16, diffusion vanes 17 and spacers 18. Each division plate 15 has a flange comprising an 85 offset part 19 closely fitting the interior of the shell 5 and a reduced part 20 of lesser diameter than the offset part to create a packing space 21 between the periphery of the reduced part and the inner wall of the 90 shell. Each of the spacers 18, of ring shape, has one edge secured, as by welding, to one face of a division plate 15, the outer surfaces of said ring resting against the inner surface of the wall formed by the reduced part 20 95 of the flange of said division plate, this constituting a particularly efficient means for securing a strong joint. The opposite edge of each spacer is provided with an inturned lip 22 that rests against the outer face of a 100 division plate in the next and adjacent section. Each diffusion plate 16 is smaller in diameter than the interior diameter of the spacers 18 to provide a passage for air around the edge of each of said plates, and a 105 lip 23 is formed on the outer edge of each diffusion plate and against which the outer ends of the diffusion vanes 17 abut. These diffusion vanes are of curved form and they are disposed as shown in Fig. 2 of the draw- 110

ings, which is a construction common to blowers of this type.

In order to preserve the peripheral speed of the fans and yet rotate them at a slower speed, the diameter of the fans and hence of the entire structure, must be increased to compensate for the slower rotation, the diametrical dimensions depending upon the rate of rotation, that is, the slower the rate 10 of rotation the greater the diameter of the fans and shell.

In order to secure lightness in construction and hence reduce the power required for operation as well as to simplify the construction, it is desirable that the structure shall be of sheet metal, but a structure composed of sheet metal shaped as in structures heretofore employed, when exceeding certain dimensions, becomes so flexible and unstable as to be practically inoperative. It is to overcome these objections and to enable the use of an extremely large sheet metal structure, the fans of which can be rotated at the desired high rate of speed, 25 that I have invented the improved blower forming the subject matter of this application.

In order to obtain this rigidity of structure I indent or dish both the division and diffusion plates as denoted by the numerals 30 24 and 25, each pair of said plates located near each other being dished in opposite directions and the dish shaped portions being substantially of the same diameter. 35 This provides an extremely stiff and rigid structure sufficient to successfully withstand any liability to twist or weave in the operation of the device and this rigidity is increased by the construction of the flanges 40 with offset and reduced parts on the division plates and the lips on the outer edges of the spacers, diffusion and end plates, it being observed that these strengthening features in each instance serve a plurality of 45 purposes, as follows:

The dishing of the division and diffusion plates as described provides a space of increased width at the periphery of each diffusion plate, and the ends of the diffusion 50 vanes are widened as at 26 to fit these spaces, and this with the lips 23 serve as a means for positioning the diffusion vanes. The dishing of the plates as above described also provides fan chambers 28 between the 55 division and diffusion plates within which fans 29 are located. The offset parts of the flanges at the periphery of the division plates provides a space for packings 32 as well as a stiffening feature for said flanges. 60 The lips 23 on the edges of the spacers provide a substantial surface to receive the plates resting against them and the lips 26 at the periphery of the end plates serve to inclose the rings and gaskets as well as to 65 stiffen this plate.

Rivets 27 are passed through the division and diffusion plates at proper intervals to secure the parts firmly together. The fans 29 are secured to a shaft 30 mounted in any suitable manner within the shell, said shaft 70 being secured to the motor shaft at one end and having a bearing in a housing 31 of any suitable construction and secured to the end plate 9. Each of the end plates 9 and 10 is also of dish shaped construction as 75 shown in Fig. 1 of the drawings, to increase the rigidity of the structure, and as a further means of securing this result the openings at the center of these end plates and through which the shaft 30 extends are 80 closed by dish shaped plates 33 and 34 preferably of a little thicker metal than the sheet metal comprising the structure as a whole. In order to strengthen the case at this point, a spider construction embodying the plates 33 and 34 is employed, this construction constituting rings 35 resting 85 against the inner end plates that occupy the same position in the end sections as do the division plates in the other sections and supported by posts or struts 37, preferably integral with the rings and with rims 38 of the closing plates. The construction secures extreme rigidity at the end of the case and the dish shaped inner and outer end plates 95 provide the inlet and exhaust chambers 39 and 40 between each pair of said plates.

Heretofore in the operation of blowers of this class, heat, due to the frictional resistance to flow through the case, and also to the compression of the air within the case, causes it to become heated to an objectionable degree. In order to prevent this excessive heating, I provide a cooling system to keep the temperature reduced by making 105 use of the spaces between the blower sections and shell or case to contain a circulating and cooling medium as water. The joints between the inturned lips 22 and the abutting division plates are made water 110 tight, as are also the other joints between the parts 19 and 20 of the flanges on the division plates and the case and spacers respectively. Circulating pipes 41 and 42 are located preferably on diametrically opposite 115 sides of the case with branches 43 extending into each of the water chambers 44, and stop-cocks or valves 45 are provided for each of the chambers to regulate the flow of water. In the construction shown herein, 120 a radiator 46 is suitably connected with the pipes 41 and 42, and a supply pipe 47 is connected with the cooling system and has a valve 48 that controls the delivery of the water to the system. A waste pipe 49 extends from the tail end of the system and contains a waste valve 50. By closing the valves 48 and 50 the water or cooling medium may be circulated over and over 125 through the system and it may be replen- 130

ished whenever desired as by opening the valves 48 and 50, and by keeping these valves open fresh water may be circulated through the system, in this event the valve 51 between the pipe 42 and radiator being closed.

The heating of the shell is greater near the exhaust end of the case than at the inlet end, and the valves 45 may be used to regulate the flow to meet this condition, a greater amount of water being permitted to flow through the chamber at the exhaust end than at the inlet end of the shell, but various arrangements of the pipes and 15 valves may be employed, and the entire construction may be varied to a greater or lesser degree and yet be within the spirit and intent of the invention, and I do not, therefore, limit my invention to the exact construction herein shown and described.

I claim—

1. A blower section comprising two plates oppositely positioned and secured together, diffusion vanes secured between said plates, 25 a spacer secured to one of said plates and surrounding the other plate at a distance from its edge, said members comprising an integral structure, a shaft extending through the center of said section, and fans 30 secured to said shaft.

2. A blower section comprising two plates oppositely positioned and secured together, diffusion vanes secured between said plates, a spacer secured to one of said plates and 35 surrounding the other plate at a distance from its edge, said parts comprising an integral structure, a shell surrounding and inclosing said sections, a shaft extending through the center of the structure, and fans 40 secured to said shaft.

3. A plural number of blower sections each comprising two plates oppositely positioned and secured together, diffusion vanes secured between the plates in each section, a spacer secured to one of the plates in 45 each section and surrounding the other plate thereof at a distance from its edge, a shell surrounding and inclosing said sections, a shaft extending through the center of said 50 structure, and fans secured to said shaft.

4. A blower comprising a sectional shell, a plate extending across the interior of the shell and located between the meeting edges of the sections, rings surrounding the shell 55 at the meeting edges of the sections, and fastening means projecting through the rings and plate to secure them together.

5. A blower comprising a sectional shell, a plate extending across the interior of the 60 shell and located between the meeting edges of the sections, rings surrounding the shell at the meeting edges of the sections, a gasket located between the rings and against said plate, and means projecting through 65 the rings and plates to secure them together.

6. A blower comprising a sectional shell, a plate extending across the interior of the shell to constitute an end wall of a section thereof, said plate being located between the meeting edges of the sections, a plate 70 located within the shell and against the first mentioned plate, a gasket located against the first mentioned plate, rings surrounding the shell at the meeting edges of the sections and located upon opposite sides of the first 75 mentioned plate and gasket, and means projecting through said rings and plate to secure the parts together.

7. A blower comprising a sectional shell, a plate extending across the interior of the 80 shell and located between the meeting edges of the sections, said plate having a peripheral lip, a member surrounding the shell and inclosed within said lip, a ring surrounding the shell adjacent to one of said meeting 85 edges, and means projecting through said plate and ring to secure the parts together.

8. A blower comprising a sectional shell, a plate extending across the interior of the shell and located between the meeting edges 90 of the sections, said plate having a peripheral lip, a ring surrounding one section of the shell adjacent to said meeting edges within the boundary of said lip, and means projecting through the ring and plate to 95 secure them together.

9. A blower comprising a sectional shell, a plate extending across the interior of the shell and located between the meeting edges 100 of the sections, said plate having a peripheral lip, a gasket located within and surrounded by said lip, rings surrounding the meeting edges of the sections, one of said rings being bounded by said lip, and means projecting through the rings and plate to 105 secure them together.

10. A blower including a shell, a blower section located within the shell and including a plate having a peripheral flange comprising two parts, one of which, the outer, enlarged offset part fits the inner surface of the shell, said plate forming one wall of a fan chamber, a fan located within said chamber, and a shaft to which said fan is secured.

11. A blower including a shell, a blower section located within the shell and including a plate having a peripheral flange with an enlarged offset portion fitting the inner surface of the shell and creating a space between said flange and shell, a fluid packing located within said space, said plate forming one wall of a fan chamber, a fan located within said chamber, and a shaft to which said fan is secured.

12. A blower including a shell, a blower section located within the shell and including a plate having a peripheral flange comprising two parts, one of which, the outer, enlarged offset part fits the inner surface of 130

the shell and a dish shaped portion near the center thereof constituting one wall of a fan chamber, a fan located within said chamber, and a shaft to which said fan is secured.

5 13. A blower including a shell, plates disposed in pairs, each member of a pair forming one wall of a fan chamber, a spacer appurtenant to each pair of plates and having a lip resting against a plate of one of said 10 pairs of plates, a fan located within said chamber, and a shaft to which said fan is secured.

14. A blower including a shell, a number of blower sections of similar construction located within the shell, each section including two plates, each of which plates forms one wall of a fan chamber, a spacer having a lip resting against a plate of one of said sections, a fan located within the fan chamber, 20 and a shaft to which said fan is secured.

15. A blower including a shell, a number of blower sections of similar construction located within the shell, each section including two plates each of which plates 25 forms one wall of a fan chamber, a spacer appurtenant to one of said plates and having an inturned lip resting against a plate of one of said sections, a fan located within the fan chamber, and a shaft to which said 30 fan is secured.

16. A blower including a shell, a number of plates located within said shell and including a pair of plates each of which forms one wall of a fan chamber, a spacer appurtenant to one of said plates and secured in contact therewith, said spacer being positioned to rest against another plate of similar construction to one of said pair of plates, a fan located within the fan chamber, and 40 a shaft to which said fan is secured.

17. A blower including a shell, a blower section located within the shell and including a plate having a peripheral flange with an enlarged offset portion fitting the inner 45 surface of the shell, a diffusion plate secured to the first mentioned plate and having a peripheral lip, diffusion vanes secured between said plates and abutting against said lip, one of said plates forming one wall of 50 a fan chamber, a fan located within said chamber, and a shaft to which said fan is secured.

18. A blower including a shell, a blower section located within the shell and including a plate having a peripheral flange with an enlarged offset portion fitting the inner surface of the shell and its central portion being dished, a diffusion plate secured to the first mentioned plate and having its central portion dished, said diffusion plate having a peripheral flange, diffusion vanes located between said plates and with their edges lengthwise thereof shaped to fit the surfaces of said plates, one of said plates

forming a wall of a fan chamber, a fan located within said chamber, and a shaft to which said fan is secured. 65

19. A blower including a shell, a blower section located within the shell and including a plate having a peripheral flange, with an enlarged offset portion fitting the inner 70 surface of the shell, a spacer having one edge secured within the smaller portion of said flange and with its opposite edge shaped into a lip to rest against an opposing surface, a diffusion plate, diffusion vanes secured between said plates, one of which plates forms one wall of a fan chamber, a fan located within said chamber, and a shaft to which said fan is secured. 75

20. A blower including a shell, a blower section located within the shell and including a plate having a peripheral flange with an enlarged offset portion fitting the inner surface of the shell, a spacer having one edge secured within the smaller part of said flange and with its outer edge having a lip to rest against an opposing surface, a diffusion plate having a peripheral lip, diffusion vanes having their edges formed to fit the facing surfaces of said plates, and the ends of said vanes abutting against said lips and one of said plates forming a wall of a fan chamber, a fan located within said chamber, and a shaft to which said fan is 95 secured. 80

21. A blower including a shell, a blower section located within the shell and including a plate having a peripheral flange with an enlarged offset portion fitting the inner 100 surface of the shell, a spacer having one edge secured within the smaller portion of said flange and its opposite end having a lip to rest against an opposing surface, a diffusion plate having a peripheral lip, each 105 of said plates being dished at their central portions and one of said plates forming a wall of a fan chamber, means for securing said plates together, diffusion vanes having their edges fitting the meeting surfaces of 110 said plates and secured between them, a fan located in said fan chamber, and a shaft to which said fan is secured. 115

22. A blower including a shell, an end plate extending across the shell, an inner plate spaced from said end plate within the shell to form a circulating chamber between them, one of said plates being dished to increase its rigidity, struts supporting the thrust of said plates one against the other, 120 a shaft extending lengthwise within the shell, and fans secured to said shaft.

23. A blower including a shell, an end plate extending across the shell, said plate being dished to increase its rigidity, an inner 125 plate spaced from said end plate within the shell to form a circulating chamber between them, struts supporting the thrust of said

- plates one against the other, a shaft extending lengthwise within the shell, and a fan secured to said shaft.
24. A blower including a shell, an end plate extending across the shell, an inner plate spaced from said end plate within the shell to form a circulating chamber between them, the latter plate being dished to increase its rigidity, struts supporting the thrust of said plates one against the other, a shaft extending lengthwise within the shell, and a fan secured to said shaft.
25. A blower including a shell, an end plate extending across the shell at one end thereof, an inner plate spaced from said end plate within the shell to form a circulating chamber between them, both of said plates being dished to increase their rigidity, struts supporting the thrust of said plates one against the other, a shaft extending lengthwise within the shell, and a fan secured to said shaft.
26. A blower including a shell, an end plate extending across the shell, an inner plate having an opening at its center and spaced within the shell from said end plate to form a circulating chamber between them, one of said plates being dished to increase its rigidity, a ring surrounding said central opening, struts extending between said ring and end plate and supporting the thrust of one against the other, a shaft extending lengthwise within the shell, and fans secured to said shaft.
27. A blower including a shell, an end plate extending across the shell and having a central opening, an inner plate having an opening at its center and spaced within the shell from said end plate to form a circulating chamber between them, one of said plates being dished to increase its rigidity, a plate closing the central opening in the end plate, struts extending from said end plate and thrusting against the inner plate adjacent to its central opening, a shaft extending lengthwise within the shell, and a fan secured to said shaft.
28. A blower including a shell, an end plate extending across the shell and having a central opening, an inner plate having a central opening and spaced within the shell from said end plate to form a circulating chamber between them, one of said plates being dished to increase its rigidity, a ring surrounding the central opening in the end plate, struts extending between said plates to support the thrust of one against the other, a shaft extending lengthwise within the shell, and a fan secured to said shaft.
29. A number of blower sections of similar construction and each including two plates oppositely positioned and secured together, diffusion vanes secured between said plates, a spacer secured to one of said plates and surrounding the other plate at a distance from its edge, said members comprising an integral structure, a shaft extending through the center of the sections, and fans secured to said shaft.
30. A blower including a shell, plates arranged in sections extending lengthwise of the shell, said sections each including a pair of plates each plate of which forms one wall of a fan chamber, spacers located upon opposite sides of one of said plates, a fan located within the fan chamber, and a shaft to which said fan is secured.
31. A blower including a shell, a number of plates arranged in sections disposed lengthwise of and within the shell, each section including a pair of plates each of which plates forms a portion of a fan chamber, one of said plates being larger in diameter than the other, a spacer located on one side of said larger plate, and another spacer having a lip resting against the opposite side of said larger plate.
32. A blower including a shell, a number of sections spaced apart within and lengthwise of the shell, each section comprising two plates oppositely disposed and each forming a portion of a fan chamber, one being larger in diameter than the other and the other having a lip at its periphery, diffusion vanes secured between said plates and within the boundary of said lip, and a spacer inclosing said smaller plate and with its inturned edge resting against the surface of the larger plate of an adjacent section, a shaft extending through the center of the shell, and fans secured to said shaft.

IRA H. SPENCER.
